UNITED STATES PATENT OFFICE

2,041,533

APPARATUS FOR MAKING SHOE SOLES

William J. De Witt and Erle Floyd Beers, Auburn,
N. Y., assignors to Dun Deer Sandals, Inc.,
Auburn, N. Y., a corporation of Delaware

Original application April 10, 1933, Serial No.
665,296. Divided and this application May 25,
1935, Serial No. 23,393

3 Claims. (Cl. 12—30)

This invention relates to an improvement in apparatus for making shoe soles being a further development of the invention disclosed in Patent No. 1,843,753, dated February 2, 1932 and has for its primary object to provide a machine for upturning one lip of the split edge of a shoe sole, one of the steps in the preparation of such soles for the assembly of shoe uppers therewith. The present application is a division of our copending application Serial No. 665,296, filed April 10, 1933.

10 In the drawing

Fig. 1 is a front elevation of one form of machine embodying this invention;

Fig. 2 is a plan view thereof; and

15 Fig. 3 is an enlarged sectional view illustrating the lip turning tool in operation.

The shoe sole 105 having been blanked and the edge having been thereafter split in any well known manner, as for example in accordance with 20 the disclosure in the above mentioned patent or application is thereby provided with lower and upper lips 106 and 107 respectively. In addition the lower lip 106 may be trimmed so that it is shorter than the upper lip 107 (see Fig. 3). This 25 further treatment is not however essential and may be omitted. The present invention relates to the upturning of the upper lip 107 by means for example of the machine 140.

The machine 140 comprises a bed plate 141 supported upon suitable legs 142 and having an opening 143 therein through which passes a shaft 144. The shaft 144, which passes through a bushed sleeve 145 suitably secured to the underside of the bed plate 141, carries at its upper end 35 a substantially rectangular block 146 and at its lower end a pulley 147 to which power may be applied in any desired manner. A hammer 148 resting upon a plate 149 and enclosed by a U-shaped cage 150 is so located on the bed plate 40 that its inner end may be engaged by the block 146. The hammer 148 is (see Fig. 2) offset with respect to the shaft and is free to reciprocate in the cage and its outer end is preferably forwardly and upwardly inclined (see Fig. 3).

45 The sole 105, placed by the operator with the lower lip 106 against the edge of the plate 149, is turned slowly until the entire split portion of the sole has passed the hammer. Each corner of the rotating block 146 forces the hammer 148 to advance and bend the lip 107 upwardly while the pressure of the sole as it is held against the plate forces the hammer to remain in contact with the block. The hammer 148 overhangs the plate 149 at all times and when the sole is positioned with 55 one side of the block against the hammer the lip

107 is initially bent upwardly. The advance of the hammer by the corners of the block forces the lip back sharply, and permanently bends it along a line determined by the contact of the lower lip 106 with the plate 149 as shown in Fig. 3.

5 While one embodiment of this invention has been shown and described it will be understood that we are not limited thereto and that other embodiments may be made without departing from the spirit and scope of the invention as set forth in the following claims.

We claim:

1. A machine for upturning one lip of a shoe sole the edge of which has been split to provide upper and lower lips, comprising a bed plate, a 15 plate mounted thereon, a hammer reciprocable over said plate, a cage fixed to said bed plate to control the direction of reciprocation of the hammer, a rotatable block against which the hammer is held by the sole being treated, the block being 20 provided with corners and means for rotating the block to advance the hammer, intermittently by the corners of the block, against a partially upturned lip of the sole to bend the same, the other lip resting against the plate mounted on the bed 25 plate to determine the location of the line along which the first mentioned lip is bent.

2. A machine for upturning one lip of a shoe sole the edge of which has been split to provide upper and lower lips, comprising a bed plate, a 30 plate mounted thereon, a hammer reciprocable over said plate, the nose thereof projecting beyond the edge of the plate, and a rotatable block for intermittently advancing the hammer, the sole to be treated acting to hold the hammer 35 against the block and being positioned with the lower lip below the nose of the hammer and in contact with the edge of the plate mounted on the bed plate and the upper lip resting against and partially upturned by the nose of the hammer 40 whereby the reciprocation of the hammer bends the upper lip upwardly along a line determined by the location of the lower lip.

3. A machine for upturning one lip of a shoe sole, the edge of which has been split to provide 45 upper and lower lips, comprising a bed plate, a plate mounted thereon, one lip of said sole resting against the edge of the last-named plate, a hammer resting upon and reciprocable over said plate into contact with and away from the other 50 lip of said sole, which has been partially upturned, to bend such lip away from the other lip of the sole, and means for actuating said hammer.

WILLIAM J. DE WITT.
ERLE FLOYD BEERS. 55
